UNITED STATES PATENT OFFICE.

JAMES A. GREEN, OF DOLGEVILLE, NEW YORK, ASSIGNOR TO DANIEL GREEN FELT SHOE COMPANY, OF BOSTON, MASSACHUSETTS, A CORPORATION OF MASSACHUSETTS.

SHOE AND METHOD OF MAKING THE SAME.

1,348,941

Specification of Letters Patent. Patented Aug. 10, 1920.

Application filed December 10, 1919. Serial No. 343,772.

To all whom it may concern:

Be it known that I, JAMES A. GREEN, a citizen of the United States, and a resident of Dolgeville, in the county of Herkimer 5 and State of New York, have invented certain new and useful Improvements in Shoes and Methods of Making the Same, of which the following is a specification, reference being made to the accompanying drawings, 10 forming a part thereof.

My invention relates particularly to improvements in the structure and methods of manufacturing turned shoes in which the vamp and upper are preferably composed of 15 felt or other pliable material, such as cotton, silk or even soft leather, while the outer sole made of a light thin leather is provided with a cushioned inner sole projecting upwardly from such outer sole within the shoe 20 which is finally molded to shape upon a last by the shrinking or contracting of the material composing the upper.

The objects of my invention are, among other things, to improve upon the methods 25 of constructing such turned shoes which are made wrong side out, turned and finally shrunk or molded to form upon a last, and also upon the finished structure of the shoe itself as made by my improved method, 30 whereby a soft-soled turned shoe or slipper is provided in which a circumferential marginal recess or pocket is formed inside the stitching which unites the outer sole and felt or pliable upper and against the marginal 35 shoulder formed by the outer edges of the padding comprised in the cushioned inner sole, such recess or pocket being used to snugly contain the sewed ridge or seam necessarily produced by the stitching together 40 of upper and outer sole without causing such sewed ridge or seam to project inwardly and extend along the exterior line of the inner tread of the shoe. By my improvements such sewed seam or ridge is also 45 wholly concealed within the shoe, thereby being fully protected against wear or loosening of the stitches since it is contained in such pocketed recess extending around the exterior line of the tread of the shoe and inside 50 the stitching uniting the felt or pliable upper to the outer sole, but wholly within the exterior surfaces of the shoe. A further feature of novelty and advantage in my invention is that the padding itself is preliminarily 55 sewed along its edges to a cloth backing at-

tached to the inner surface of the outer sole after being fully extended in all directions over the sole which prevents the displacement, "creeping" or "bunching" of such padding in the shoe, either during the successive steps in the making of the shoe, or thereafter when the shoe is worn, while at the same time providing the desired shoulder forming the inner side of the marginal recess extending around the inner tread of the shoe.

With these and other objects in view, the invention comprises not only the shoe having the novel features of construction herein shown and described, but also in the improved methods of making the shoe, the invention being further described herein and then particularly pointed out in the appended claims.

In the accompanying drawings showing 75 the invention in a preferred embodiment of a shoe having a felt upper and thin leather outer sole, Figure 1 is a plan view illustrating the padding for the cushioned inner sole stitched to the cloth backing secured 80 to the inner side of the outer sole;

Fig. 2 is a detail sectional view taken on the line 2-2 shown in Fig. 1;

Fig. 3 is a sectional view taken on the line 3-3 shown in Fig. 1;

Fig. 4 is a detailed sectional view illustrating the manner of stitching together the upper, outer sole and cloth backing along their outer edges, taken on the line 4-4 shown in Fig. 5;

Fig. 5 is a plan view illustrating the upper, outer sole and cloth backing sewed together;

Fig. 6 is a fragmentary side view of the heel portion of my improved shoe looking 95 in the direction of the arrow shown in Fig. 5 before the inner sole or "sock lining" is attached;

Fig. 7 is a plan view illustrating the inner sole partly secured to the theretofore 100 assembled upper, outer sole and cloth backing having the padding attached thereto;

Fig. 8 is an enlarged sectional view taken on the line 8-8 of Fig. 7;

Fig. 9 is a side elevation of the completed 105 shoe or slipper;

Fig. 10 is a sectional view of the completed shoe, the tread portion being shown in elevation; and

Fig. 11 is a sectional view of the shoe be- 110

ing shrunk or molded to form upon a last, the view being taken upon line 11—11 in Fig. 10.

Similar numerals refer to similar parts throughout the several figures.

By way of example I will set forth my improved method of making these turned shoes or slippers as shown in the drawings as heretofore stated in connection with a 10 soft-soled felt shoe, and is preferably practised as follows:—The upper 12 composed of felt or other pliable material is first cut to proper form and stitched at the rear end of the shoe as indicated at 13 shown in Fig.

15 6. Preferably a separate piece or welt 14 of the same material is sewed in around the heel portion and at the bottom of the stitching 13 to form a suitable pocket for a heel pad to be thereafter placed therein when 20 the parts of the shoe are assembled and sewed together before the shoe is turned and shrunk or molded to form upon a last. The stitching 16 unites the upper edges of the welt 14 to the lower edges of the upper 25 12 about the heel portion as shown in Fig. 5. The outer sole 15 comprising preferably a single piece of thin leather is then cut to the shape and size required by the length and width of the felt shoe or slipper proper.

30 The cushioned inner sole or "sock lining" for the inner tread of the shoe is formed by first securing a padding 17, preferably composed of hair-felt or carded wool and cut in a slightly smaller size and less area than the 35 outer sole 15, to a cloth backing 18 by the stitching 19, preferably zig-zag in formation, along the outer edges of the padding as shown in Figs. 1 and 2, after the padding 17 has been carefully laid flat upon the backing 40 18, the stitching 19 serving to not only secure the padding to the cloth backing, but also to retain such padding in place against disarrangement "creeping" or "bunching" of such padding, either during the process 45 of manufacture or when the shoe is worn.

As shown in Figs. 1 and 3, the padding 17 is arranged on the backing 18 and outer sole 15 to leave a marginal space or recess 20 inside its outer edges. The stitching 19 in 50 conjunction with the exterior edges of the padding 17 form a shoulder 21 extending along the exterior line of the tread of the shoe somewhat inside the outer edges of the outer sole 15 and cloth backing 18, such 55 shoulder 21 forming one side of the marginal space 20 which provides a recess to contain the stitched seam joining the upper 12 to the outer sole 15 with its thereto secured backing 18.

60 After the padding 17 has been secured to the backing 18 by the zig-zag stitching 19, the backing is secured to the inner side of the outer sole 15 by a layer 22 of glue, paste or other adhesive as shown in Fig. 3. Then 65 this outer sole 15 with the padding 17 se-

cured thereto as just explained is secured along its outer edges by stitching 23 to the lower outer edges of the upper 12 and welt 14 as shown in Figs. 4 and 5, these parts being united to form the general structure of 70 the shoe, while each is wrong side out; such stitching 23 extends along the outer side of the marginal space 20 as shown in Fig. 4, and thereby attaches the upper 12 to the outer sole 15 and backing 18 by the sewed 75 ridge or seam 24 extending around the inner tread of the shoe after the latter has been turned and lasted, the seam 24 being turned inwardly to be tucked away and contained within the recess 20 as particularly shown in Figs. 8 and 10. While the shoe is in this stage of formation a heel pad 25, also preferably made of hair-felt or carded wool and cut to shape to form a spring heel within the heel 80 portion of the shoe about the welt 14, is placed upon the heel portion of the padding 17, as shown in Fig. 8, and then the inner sole or sock lining 26 cut to shape to cover the pad and padding is secured over such 85 padding 17 and heel part 25 by a line of stitching 27 running along the sewed ridge or seam 24 adjacent the outer edges of the upper 12, welt 14, outer sole 15 and cloth 90 backing 18. Such stitching 27 may readily be performed by a machine thereby avoiding hand sewing heretofore used in attaching the inner sole 26 to the upper 12 and welt 14. Where a shoe or slipper without 95 a spring heel is desired, I omit the heel pad 100 25 and the welt 14 which forms the pocket in the upper suitable for the heel pad when the shoe is turned, the inner sole 26 then covering the padding 17 throughout its 105 length and being sewed to the lower edges 105 of the upper 12 by the stitching 27 extending along the entire outer edge of the upper 12 and throughout the entire extent of the outer sole 15, adjacent the seam 24.

After the shoe is brought to the stage 110 shown in part by Fig. 8, the shoe is practically finished so far as assembling and securing the component parts together. The shoe is now to be turned and shaped or molded to the desired form, and to accomplish this readily the upper 12 is wetted slightly, and the shoe is turned right side out as shown in Figs. 9 and 10. The upper of the shoe is now thoroughly dampened or wetted by plunging same in water, after 115 120 which preferably a hollow bottom last 28 is inserted within the interior parts of the shoe as shown in Fig. 11, thereby slightly stretching the upper 12 and at the same time forcing the inner cushioned sock lining 125 upwardly into the concave recess of the last to form a slightly arched inner sole affording the desired soft cushion for the sole of the foot. However an ordinary flat-bottomed last may be used in place of the hol- 130

low bottom last 28, though with obviously less advantageous results. During the drying process while the shoe is on the last 28, the felt upper shrinks and molds itself to 5 the shape and contour of the last, and the outer leather sole 15 is stretched flat while the sewed ridge or seam 24 is thereby forced within, and is contained by, the marginal recess 20 extending around the exterior 10 tread of the shoe, so that such seam 24 can not project within the tread of the shoe to be felt by the foot when the slipper is worn.

It will be observed that all the stitching steps in my improved method of making 15 these felt shoes or slippers may be readily performed by machinery, thereby saving greatly in labor and time in producing such shoes. And further it will be particularly understood that the marginal recess 20 20 formed just inside the outer edges of the upper and outer sole against the shoulder formed by the hair-felt padding being firmly secured to the inner side of such outer sole, provides sufficient space into 25 which the sewed ridge or seam 24 may be forced into the recess 20 through the shrinking of the shoe on the last, within which recess this prominent seam may be tucked away and concealed without exposing the 30 stitching 23 to possible loosening or wear, and without having the seam project upwardly along the exterior line of the inner tread of the shoe; furthermore the forming of a fixed shoulder by securely attaching the 35 edges of the padding to the cloth backing thereafter pasted to the outer sole prevents the padding from undesirably "creeping" or "bunching" along the inner side of the outer sole.

40 While the shoe structure and method of making same embody the invention in its preferred form, it will be understood that changes and variations may be made in the various detailed features without departing 45 from the principles and scope of the invention herein disclosed.

I claim as my invention:—

1. The method of making shoes which consists in securing a padding on the inner 50 side of an outer sole inside the outer edges of said sole, then attaching said outer sole with the thereto secured padding to an upper, all the parts being wrong side out, then securing an inner sole over said padding, then turning the shoe so made right side out, and finally lasting same to form.

2. The method of making shoes which consists in securing a padding on the inner side of an outer sole by a line of stitching 60 inside the outer edges of said sole, then attaching said outer sole with the thereto secured padding to an upper by a line of stitching along the outer edges of the outer sole and upper, all the parts being wrong 65 side out, then securing an inner sole over

said padding, then turning the shoe so made right side out, and finally lasting same to form.

3. The method of making shoes which consists in stitching a padding along its 70 outer edges to a backing and thereafter securing the backing to the inner side of an outer sole, said stitching extending inside the outer edges of said sole, then attaching said outer sole with the thereto secured 75 padding to an upper, all the parts being wrong side out, then stitching an inner sole over the padding along the outer edges of the sole and upper, then turning the shoe so made right side out, and finally lasting 80 same to form.

4. The method of making shoes which consists in stitching a padding along its outer edges to a backing and thereafter securing the backing to the inner side of an 85 outer sole, said stitching extending inside the outer edges of said sole, then attaching said outer sole with the thereto secured padding to an upper by a line of stitching along the outer edges of the outer sole and 90 upper, all the parts being wrong side out, then stitching an inner sole over the padding along the outer edges of the sole and upper, then turning the shoe so made right side out, and finally lasting same to form. 95

5. The method of making shoes which consists in securing a padding on the inner side of an outer sole inside the outer edges of said sole, then attaching said outer sole with the thereto secured padding to an upper having a welt extending around the heel portion of the shoe, all the parts being wrong side out, then laying a pad over the heel portion of said padding, then securing an inner sole over said pad and padding, then turning the shoe so made right side out, and finally lasting same to form. 100

6. The method of making shoes which consists in securing a padding on the inner side of an outer sole by a line of stitching inside 110 the outer edges of said sole, then attaching said outer sole with the thereto secured padding to an upper having a welt extending around the heel portion of the shoe by a line of stitching along the outer edges 115 of the outer sole, upper and welt, all the parts being wrong side out, then laying a pad over the heel portion of said padding, then securing an inner sole over said pad and padding, then turning the shoe so made 120 right side out, and finally lasting same to form.

7. The method of making shoes which consists in stitching a padding along its outer edges to a backing and thereafter securing the backing to the inner side of an outer sole, said stitching extending inside the outer edges of said sole, then attaching said outer sole with the thereto secured 125 padding to an upper having a welt extend- 130

ing around the heel portion of the shoe, all the parts being wrong side out, then laying a pad over the heel portion of said padding, then stitching an inner sole over said pad 5 and padding along the outer edges of the sole, upper and welt, then turning the shoe so made right side out, and finally lasting same to form.

8. The method of making shoes which 10 consists in stitching a padding along its outer edges to a backing and thereafter securing the backing to the inner side of an outer sole, said stitching extending inside the outer edges of said sole, then attaching 15 said outer sole with the thereto secured padding to an upper having a welt extending around the heel portion of the shoe by a line of stitching along the outer edges of the outer sole, upper and welt, all the parts 20 being wrong side out, then laying a pad over the heel portion of said padding, then stitching an inner sole over said pad and padding along the outer edges of the sole, upper and welt, then turning the shoe so 25 made right side out, and finally lasting same to form.

9. A turned shoe comprising a molded upper stitched to an outer sole along their respective inturned outer edges combined 30 with an upwardly projecting cushioned inner sole of less area than said outer sole thereby providing a marginal recess inside said stitching to contain the inturned stitched seam uniting the upper and outer sole.

35 10. A turned shoe comprising a molded upper stitched to an outer sole along their respective inturned outer edges combined

with an upwardly projecting cushioned inner sole of less area than said outer sole, said cushion being secured along its edges 40 to said outer sole, thereby providing a marginal recess extending around the tread of the shoe between said stitching and said cushioned inner sole to contain the inturned 45 stitched seam uniting the upper and outer sole.

11. A turned shoe comprising a molded upper stitched to an outer sole along their respective inturned outer edges combined with an upwardly projecting cushioned inner sole of less area than said outer sole, 50 said inner sole being stitched to said upper and outer sole along the stitching uniting the same, thereby providing a marginal recess 55 extending around the tread of the shoe inside said stitching to contain the inturned stitched seam uniting the upper, cushioned inner sole and outer sole.

12. A turned shoe comprising a molded upper stitched to an outer sole along their respective inturned outer edges combined with an upwardly projecting pad of less area than said outer sole, said pad being held 60 flat to said outer sole by stitching along its edge and an inner sole stitched to said upper and outer sole along the stitching uniting the same and outside the stitching for said pad, thereby providing a marginal recess 65 extending around the tread of the shoe inside said outer sole stitching to contain the 70 outer inturned stitched seam uniting the upper, pad, inner sole and outer sole.

JAMES A. GREEN.
